UNITED STATES PATENT OFFICE.

CHARLES A. WAITZ, OF ROUSEVILLE, PENNSYLVANIA.

PUMP.

Application filed October 28, 1925. Serial No. 65,234.

The invention is particularly directed to improving oil well pumps, the working barrels of which are provided with liners. These liners are ordinarily made of brass or similar material and rather thin walls in order to give them the proper size and as a consequence the threads on which the liners are of very fine pitch, an entirely different pitch than the threads of the tubing, or working barrel. In use a liner becomes locked with the working barrel through corrosion or deposits and in attempting to disconnect the working barrel from the coupling carrying the valve seat the thread of the liner is usually stripped due to the difference in pitch. One of the purposes of the present invention is to obviate this difficulty. Another feature of the invention is the threading of the liner at both ends so that it may be reversed, thus varying the part of the liner on which the more severe wear takes place. Features and details of the invention will appear from the specification and claims.

The invention is illustrated in the accompanying drawings as follows:—

The drawing shows a vertical section of a pump.

1 marks the ordinary removable working barrel, 2 the tubing extending from the working barrel, 3 the coupling fitting at the lower end of the working barrel, 4 the strainer pipe extending from the coupling, 5 the liner, 6 the pump plunger, 7 the pump plunger stem or continuation of the sucker rod, 8 the standing valve, and 9 the standing valve seat or fitting.

The standing valve fitting is connected with the coupling fitting 3 by means of a nipple 10, this nipple having a screw-threaded connection 11 with the fitting 9 and a screw-threaded connection 12 with the coupling fitting 3. The working barrel 1 has a screw-threaded connection 13 with the coupling fitting 3 and the pitch of the screw thread 13 is similar to the pitch of the screw-threaded connections 11 and 12. When, therefore, the tubing is drawn and it is desired to remove the liner and the standing valve the working barrel is unscrewed from the coupling 3 and if the liner has become fixed with the working barrel through corrosion or deposits the nipple 10 will be unscrewed from one of the connections 11, or 12 coincidentally with the unscrew-

ing of the connection 13 and inasmuch as the pitch is the same the threads of neither are stripped. The liner is connected with the fitting 9 through an internal screw thread on the liner and this is set up against a shoulder 9^a and this connection is also of larger diameter than the nipple connection so that in practice the nipple connection is always unscrewed rather than the threaded connection between the liner and the fitting 9. Consequently there is no stripping of the threads of the liner.

I prefer to provide the upper end of the liner with internal screw threads 14 similar to the internal screw threads at the bottom so that in practice when the liner is removed it may be reversed, thus varying the parts of the barrel which are subjected to most severe wear. In order to avoid the wearing of the threads 14 the coupling 15 on the stem 7 is sufficiently large to project over the edge of the liner into contact with the walls of the tubing so as to prevent the wearing of the threads by the stem 7.

What I claim as new is:—

1. In a pump, the combination of a working barrel; a liner; a fitting; a screw connection between the bottom of the barrel and the fitting; and a nipple between the liner and the fitting having its screw threads of the same pitch as the screw connection.

2. In a pump, the combination of a working barrel; a liner; a standing valve fitting to which the liner is screwed; a coupling; a screw connection between the coupling and the working barrel; and a nipple between the standing valve fitting and the coupling, the screw pitch of the nipple being the same as the screw connection between the working barrel and the coupling.

3. In a pump, the combination of a working barrel; an externally threaded standing valve fitting; a liner internally screw threaded at both ends and screwed on to the fitting; a plunger in the liner; a sucker rod extending from the plunger; and a projection on the sucker rod maintaining the sucker rod clear of the thread on the inside of the upper end of the liner.

In testimony whereof I have hereunto set my hand.

CHARLES A. WAITZ.
